UNITED STATES PATENT OFFICE.

MARY A. OLIVER, OF OSWEGO, NEW YORK.

DESIGN FOR A BOTTLE-HOLDER.

SPECIFICATION forming part of Design No. 21,280, dated January 5, 1892.

Application filed September 28, 1891. Serial No. 407,081. Term of patent 3½ years.

To all whom it may concern:

Be it known that I, MARY A. OLIVER, of Oswego, in the county of Oswego and State of New York, have invented a new and original Design for a Bottle-Holder, of which the following is a specification.

The accompanying drawing represents a perspective view of a bottle-holder shaped in accordance with my design.

10 The body of the holder is shaped practically as a hollow truncated cone, appearing open at its upper end and at its lower end as meeting a flaring cylindric base. A figure simulating the spout and nose of a water-
15 ing-can is located at one side of the body and apparently unites with it.

The above constitute the leading features of the design, and the adjunctive features consist of a rod or strap like figure bowed over the top of the body of the holder and curved 20 downward at one side thereof. The rod or strap like figure simulates an ornamental handle, as a cord or ribbon is apparently wound around it, and a bow is represented as further decorating the handle. 25

I claim—

The design for a bottle-holder, as shown and described.

MARY A. OLIVER.
